J. H. NELSON

WHEEL SUPPORTING FORK FOR BICYCLES AND THE LIKE

Filed April 20, 1923

Inventor:
John H. Nelson

By *John H. Nelson*
Atty's

UNITED STATES PATENT OFFICE.

JOHN H. NELSON, OF CHICAGO, ILLINOIS.

WHEEL-SUPPORTING FORK FOR BICYCLES AND THE LIKE.

Application filed April 20, 1923. Serial No. 633,417.

To all whom it may concern:

Be it known that I, JOHN H. NELSON, a citizen of the United States, residing at Chicago, in the county of Cook and State 5 of Illinois, have invented a certain new and useful Wheel-Supporting Fork for Bicycles and the like, of which the following is a specification.

The invention pertains to bicycles and like 10 vehicles, and has especial reference to an improved construction for the steering wheel fork.

The object of the invention is to provide a fork of a thoroughly practical character, 15 which possesses great strength and rigidity; which may be manufactured at a low cost; and which presents a neat and ornamental appearance.

In the accompanying drawings I have 20 illustrated a fork construction embodying my invention in its preferred form. I wish to point out, however, that it is contemplated that various changes in the construction and arrangement of the parts may be made by 25 those skilled in the art, without departing from the spirit and scope of the invention as expressed in the appended claims.

Figure 1 of the drawings is a side elevational view of my improved fork. Fig. 2 30 is a front view of the same. Fig. 3 is a sectional view taken in the plane of line 3—3 of Fig. 1 but on an enlarged scale. Figs. 4, 5 and 6 are elevational views of several of the parts in detached relation. 35 Fig. 7 is a fragmentary front elevational view partly in section illustrating details of construction. Fig. 8 is a fragmentary sectional view taken substantially in the plane of line 8—8 of Fig. 7.

The fork comprises generally a bifurcated 40 lower portion 10 adapted to straddle the wheel to be mounted thereon, such as the steering wheel of the bicycle, and a shank 11 which is adapted to be supported in the bicycle frame, and to which the handle bars 45 are secured in the usual way.

I preferably construct the bifurcated portion 10 from solid rod stock, bent to form front, rear and intermediate members 12, 50 13 and 14. The front and rear members 12 and 13 are of U-shape and preferably are made from a single piece of stock by bending it first substantially midway between its ends (see Fig. 5) to form one of the members 12, 13, and then doubling the arms 55 of the U-shape structure thus formed back

upon themselves substantially midway between their ends and bringing them together at their free ends to form the other one of said members 12, 13. In the construction 60 herein shown the rear member 13 is first formed, and the forward member 12 is completed by connecting the free ends of the rod as shown in broken lines at 16, Fig. 2.

In the present instance I employ two intermediate members 14 made from separate pieces of rod stock but secured at their upper ends to the head 19 so as to be in effect integrally connected thereby to form a single U-member when the parts are welded together as hereinafter set forth. These separate pieces are shaped at their lower ends as shown at 17 (Fig. 6) so as to enter snugly between the arms of the front and rear members 12 and 13. At their upper ends they 75 are curved inwardly as at 18 (Fig. 7) for a purpose which will presently appear.

In fastening the parts of the bifurcated portion 10 to the lower end of the shank 11 I employ at the lower end of the shank a 80 tubular head 19 adapted to receive snugly the lower end of the shank. In the front and rear sides of this head near the lower end thereof I provide recesses in the form of transverse grooves 20 adapted to receive the upper ends of the front and rear members 12 and 13; and upon opposite sides of the head I provide recesses or apertures 21 to receive the upper inwardly extending ends of the intermediate members 14.

The parts of the lower bifurcated portion 10 are secured together at their lower ends by welding, and the upper ends of such parts are secured to the head and the latter secured to the shank also by welding. 95 In the first welding operation, the lower ends of the opposite side arms of the members 12 and 13, with the members 14 entered therebetween, are placed in a suitable die of a press which is equipped so as to perform 100 the welding operation while simultaneously exerting pressure upon the parts. Thus the lower ends of the fork are shaped and welded in a single operation to form in effect integral toe portions as shown in Figs. 1 and 105 3, which is finally drilled near the lower free ends of the opposite side portions to provide apertures 22 for the wheel journal. This shaping operation may include the curving of the lower ends of the fork as 110 shown in Fig. 1, where this is desired.

In the next operation, the members 12

and 13 are entered in their grooves 20 in the head 19, and the upper ends of the intermediate members 14 are entered in the apertures 21 provided therefor. Then with the shank 11 entered into the head, the parts are placed in a suitable die in the press and in one operation rigidly welded together. In this operation also the free ends of the rod from which the front and rear members of the lower bifurcated portion 10 are formed are secured together.

It will be observed from Figs. 2 and 7 that the intermediate members 14 of the fork are so proportioned as to extend outwardly and upwardly beyond the sides of the front and rear members 12 and 13, so as to produce an effect of symmetry.

It will be seen that in making my improved fork I employ materials of relatively low cost, and form and assemble the parts with a minimum labor expenditure. It will also be observed that I have produced a fork of a very rugged character, capable of withstanding extreme strains and not subject to breakage when the strain is too great, as is the case with the common tubular construction employed. At the same time the fork presents an appearance pleasing to the eye, lending itself readily to preferred ornamentation.

I claim as my invention:

1. A wheel carrying fork comprising a shank, and a bifurcated lower portion having U-shaped members disposed one in front of the other with their corresponding lower ends integral and their upper ends bowed and rigidly secured upon opposite sides of said shank.

2. A wheel supporting fork comprising a shank, a head rigidly secured to the lower end of the shank and a lower bifurcated portion having integral front and rear U-shaped members, the upper ends of said members being bowed and rigidly secured to the head in spaced relation.

3. A wheel supporting fork comprising a head member and a bifurcated portion comprising integral U-shaped members disposed one in front of the other, and having bowed upper ends said head having recesses in which the bowed ends of the front and rear members are entered and rigidly secured.

4. A wheel-supporting fork comprising a

head, and a bifurcated portion comprising front, rear and intermediate members rigidly secured together at their lower ends and having their upper portions rigidly secured to said head, the front and rear members being U-shaped with bowed upper end portions.

5. A wheel-supporting fork comprising a head, and a bifurcated portion comprising front, rear and intermediate members rigidly secured together at their lower ends and having their upper portions rigidly secured to said head, certain of said members being so proportioned as to extend upwardly and outwardly beyond the adjacent members.

6. A wheel-supporting fork comprising, in combination, a head and a bifurcated portion comprising front and rear side members at each side of said head integrally connected at their lower ends and rigidly secured at their upper ends upon the front and rear sides of said head, and a reinforcing means comprising intermediate members secured at their lower ends between the front and rear members and at their upper ends to said head substantially midway between the front and rear members, said head having apertures to receive the upper ends of said intermediate members.

7. A wheel supporting fork consisting of a single piece of solid rod stock bent to form two U-shaped members disposed one in front of the other with the lower ends of the two members integrally connected at corresponding sides, the upper end portions of the two members being bowed, and a head on the opposite sides of which said bowed ends of the members are rigidly secured.

8. A wheel supporting fork consisting of a single piece of solid rod stock bent to form two U-shaped members disposed one in front of the other with the lower ends of the two members integrally connected at corresponding sides, the upper end portions of the two members being bowed, and a head on the opposite sides of which said bowed ends of the members are rigidly secured, said head having recesses adapted to receive the bowed upper ends of the two members.

In testimony whereof, I have hereunto affixed my signature.

JOHN H. NELSON.
